UNITED STATES PATENT OFFICE.

FRANK W. NELSON, OF CHICAGO, ILLINOIS, ASSIGNOR OF ONE-THIRD TO
LYMAN B. COE, OF SAME PLACE.

BIT.

SPECIFICATION forming part of Letters Patent No. 548,385, dated October 22, 1895.

Application filed June 8, 1895. Serial No. 552,115. (No model.)

To all whom it may concern:

Be it known that I, FRANK W. NELSON, a citizen of the United States, residing at Chicago, in the county of Cook and State of Illinois, have invented a new and useful Improvement 5 in Bits, of which the following is a specification.

My invention relates to an improvement in the tool known as a "bit," and which involves 10 as its parts a stem adapted to be inserted at one end into and fastened in a suitable holder or handle and provided at its opposite pointed end with a rotary cutter.

More particularly stated, my invention relates, primarily, to an improvement in the 15 class of bits having the cutter portion in the form of a readily removable and replaceable attachment on the stem to afford what may properly be termed a "multiple tool" possessing the attribute of economy in the matter 20 of original cost and in that of its use by adapting the same stem to be used for cutters of many different sizes or varieties.

My object is to provide an improved construction of the cutter-head of a bit, and particularly, though not exclusively, of a bit having 25 a removable and replaceable cutter-head; and my further object is to provide a generally-improved construction of interchangeable bit.

Referring to the accompanying drawings, Figure 1 shows my improved bit by a view in elevation. Fig. 2 is an enlarged broken sectional view of the same with the gage omitted; 35 Fig. 3, a view in elevation of the gage-holder; Fig. 4, an end view of one of the attachable and separable cutter-heads; and Fig. 5, a view of the same in elevation, showing a modification.

40 A is the stem, provided at one end with a head *r*, adapted to be inserted into a holder or handle, (not shown,) and which stem should be of uniform or substantially uniform diameter throughout from the head to a circumferential shoulder *q*, provided near its opposite end, and from which it tapers by preference only to a point *x*, whence it may be uniform in diameter to the point *t*, which should be screw-threaded. On the stem is provided 45 a suitable spring-catch device or lock *B*, a desirable construction of which is that illus-

trated, involving a recess *p*, formed in the stem and undercut in its upper end, while from the lower end of the recess, which may be straight, extends a slot *p'* lengthwise of 55 the stem to the shoulder *q*, toward which its depth increases. The catch is formed of a bar or strip of springy metal, provided at one end with a head *o*, conforming in shape to that of the recess *p*, which it enters, the bar being provided toward its lower end with a button *o'* and at its lower end with a stud or key *o*², projecting at a right angle, and the extent of the projection of which should not be greater than the extent of its play in the slot 60 *p'*, in order that by depressing the bar at its button *o'* the outer surface of the stud may be brought flush with the circumferential surface of the stem *A*.

C is the tubular cutter-head, adapted at 70 will to be applied to and removed from the stem *A*. It is of the general somewhat cylindrical form illustrated, the longitudinal opening through it conforming to the external contour of the stem from a point above the 75 shoulder *q* to or nearly to the point *t*, whereby it contains an internal shoulder *q'* to meet the shoulder on the stem. In the body of the head *C* is formed a longitudinal slot *o*³ at a point to coincide with the key *o*² when the 80 head is adjusted on the stem to a point at which the shoulders *q* and *q'* meet, the adjustment being effected by depressing the catch-bar at its button *o'* and slipping upon the stem from its point end a head *C* till 85 stopped by abutment of the shoulders, when on releasing the button the key *o*² will spring into the slot *o*³, and thus engage the cutter-head to hold it in place. Of course the key 90 *o*² must not project beyond the external surface of the cutter-head, so that the depth of the slot *o*³ in the direction diametrically of the cutter should at least equal the width in the corresponding direction of the stud. In a cutter-head of the larger size the thickness of 95 metal of its body portion may be sufficient to have the slot *o*³ formed therein, as shown in Fig. 5, and the spiral rib *n* about the body portion may then be narrow, as represented in that figure; but in the smaller sizes of the 100 head, the metal of the body portion not being thick enough for a slot *o*³ as deep as the

width of the key o^3 , as it is required to be for all of the various sizes of interchangeable heads for the tool, the spiral rib n should be accordingly wider, as represented in Fig. 1, 5 in order that the slot o^3 may be formed through the additional thickness of metal it affords. The spiral rib starts at the upper end of the head C and terminates at the lower end thereof in a knife-edge v , extending from a point 10 or nearly in line with the longitudinal center of the head to the outer circumference thereof, where, moreover, behind the plane of said cutting-edge there is provided a downward-extending cutting lip or point w . Close 15 to the central opening through the head C on its lower end I provide another and narrower cutting-edge v' and behind and adjacent to it on the external side of the arc of which it forms the terminus (and which is concentric with the arc on which the point w is provided) a downward-extending cutting lip or point w' . Thus the head is provided on its 20 lower end with an inner cutter-edge and inner cutter-point and an outer cutter-edge and 25 outer cutter-point, whereby the cutting action is facilitated, and the shavings which are cut must be sufficiently narrow to pass freely along the spiral afforded by the spiral rib n , and thus avoid clogging the tool in boring. 30 It will also be observed that the button o' is so shaped as to tend to assist the shavings rather than obstruct them in receding out of the hole being bored.

A large number—say twenty or more—of 35 different sizes of the cutter-heads C , all, however, having the same internal shape and diameter, may be interchangeably used on the same stem A , the shoulders q and q' always preventing any tendency in the tapering 40 stem when used in boring to become unduly tightened by wedging in the head; and thus I practically provide as many different bits as may be adapted for use on the one stem, thereby affording to my improved tool the 45 tributes of economy hereinbefore referred to.

To gage the depth of penetration of the tool, I provide on the stem a gage D , adjustable for any depth to be bored in proportion to the length of the stem. As shown, the gage 50 comprises a skeleton skirt m , terminating at its lower end in a ring m' , much greater in diameter than the stem A , and converging toward its opposite end into a circumferentially-grooved collar m^2 , which loosely fits 55 about the stem; and l is an annular head surrounding the stem and carrying a set-screw l' , by which to fasten it thereon at any point

to which it may be moved, the head being provided with a depending flange l^2 , having an inward-extending lip l^3 and reaching only 60 part way about the annular head, whereby it may be engaged with the collar m^2 by inserting the lip l^3 into the groove thereof, when the whole may be slipped on the stem (as from its upper end) and up or down thereon to the desired point, at which the gage may be fastened by suitably turning the set-screw l' . 65

What I claim as new, and desire to secure by Letters Patent, is—

1. A cutter-head for a bit provided with an external spiral rib terminating at its lower end 70 in a cutting-edge v , an outer cutting-point w and an inner cutting-edge v' on the lower end of the head, and an inner cutting-point w' on an arc described on said lower end of the head, said cutting-edge v extending in a line tangential to the circle on which said arc is described, substantially as and for the purpose set forth.

2. A cutter-head for a bit separable from 80 and attachable on the stem of the tool and comprising a hollow head adapted to fit about and be fastened on said stem, the head being provided with an external spiral rib terminating at its lower end in a cutting-edge and having an outer cutting point, and an inner cutting-edge and an inner cutting-point on the lower end of the head, substantially as described.

3. A bit comprising a stem A provided with 85 fastening means B , a cutter-head separable from and attachable on the stem and comprising a hollow head provided with a slot o^3 , at which it is engaged by said fastening means, the head having an external spiral rib n and terminating at its lower end in a cutting-edge v and having an outer cutting-point w , and an inner cutting-edge v' and an inner cutting-point w' on the lower end of the head, substantially as described.

4. In combination with a bit, a gage D adjustably fastened upon the bit stem and comprising a skirt-portion m terminating at one end in a ring m' and at its opposite end in a grooved collar m^2 immediately and loosely surrounding the stem of the bit, and an annular head l provided with a set-screw l' and with a flange l^2 having a lip l^3 to enter and engage the collar at its groove, substantially as described.

FRANK W. NELSON.
